UNITED STATES PATENT OFFICE.

BELDEN L. CONCHAR, OF MAPLEWOOD, NEW JERSEY.

MOPSTICK HEAD.

Application filed June 16, 1923. Serial No. 645,745.

To all whom it may concern:

Be it known that I, BELDEN L. CONCHAR, a citizen of the United States, residing at Maplewood, in the county of Essex and State of New Jersey, have invented certain new and useful Improvements in Mopstick Heads, of which the following is a full, clear, and exact description.

This invention relates to mop stick heads having a groove along the outer end edge in which mop cords or cloths may be clamped by a wire or other clamping element which passes along the groove and is adjustably secured to the handle. Devices of this type commonly employ a cylindrical coil spring which is secured at one end to the mop stick adjacent the grooves or clamping head, and which is articulately connected to the means for operating the wire or clamping element into and out of clamping engagement with the head. The coil spring is commonly anchored against movement endwise of the stick by a staple which also serves to anchor the cross head to the end of the mop stick. It is necessary to prevent the coil spring from rotating about the mop stick as an axis, because such a rotation might disengage the spring from beneath the staple and allow it to slide endwise down the mop stick. The mop stick is commonly cylindrical and fits in a cylindrical socket in the cross head, the staple which anchors the head to the stick serving, with the tight fit between the stick and socket, to prevent rotation of the head relatively to the stick. The moisture to which the mop is continuously subject soon rots the wood around the staple sufficiently to cause the head to become loose and hinder the manipulation of the mop in use.

An object of the invention is to provide an improved mop of this type in which relative rotation between the clamping head and mop stick will be effectively prevented; in which the spring will be effectively held against turning upon the mop stick without reliance upon the anchoring staple; with which the assembly of the parts of the mop is facilitated; and which is relatively strong, durable and inexpensive. Various other objects and advantages will be apparent from the following description of an embodiment of the invention, and the novel

features will be particularly pointed out hereinafter in claims. 55

In the accompanying drawing:

Figure 1 is an elevation of a mop constructed in accordance with the invention;

Fig. 2 is an end view of the same;

Fig. 3 is a section through the same taken substantially along the line 3—3 of Fig. 1. 60

In the illustrated embodiment of the invention two sheet metal stampings 1 and 2 are secured together, face to face, in any suitable manner such as by interlocking cut out tongues 3. The stampings at their outer ends are bent away from one another so as to form a shoulder and then substantially at right angles thereto, as at 4, which will be parallel to their original planes, to form between the last mentioned angular portions a U-shaped channel or groove in which the mop cloths 5 may be clamped by a bail or clamp element 6. Before being attached together, the stampings at their inner ends are drawn outwardly in opposite directions, relatively to one another, as at 7 and 8, to form between them a non-circular socket for receiving the end of a mop stick 9. The mop stick 9 is cylindrical in shape, but at the end secured to the cross head has a segmental portion cut away to form a flat plane surface 10. The drawn portion 8 of one of the stampings has a flat portion corresponding to that of the stick 85 so that the socket will conform to the periphery of the received end of the mop stick. The socket is of such a size that the end of the mop stick will fit tightly therein, and a staple, tack, or other suitable securing means 11 may be used for anchoring the cross head to the end of the mop stick. 90

A helical coil spring 12 is provided upon the end of the mop stick which fits into the cross head, and loosely surrounds the same so as to freely slide thereon when free to do so. The end of the spring 12 adjacent the cross head has one or more turns of lesser diameter than the remainder of the spring so as to closely engage or fit the non-circular periphery of the stick, with at least one of the close turns flattened, as at 12, so as to hug closely the flat surface 10 of the mop stick or the flat portion of the socket and beyond the same in close engagement 105 with either the periphery of the stick or the

outer surface of the socket portion 8 of the cross head. In order to turn the spring around the stick it will be necessary to flex the turn or turns which are flattened over 5 the flat surface 10 and the flat surface of the socket or cross head, and the force necessary to effect this flexing will resist the rotation of the spring. The forces tending to cause rotation of the spring on the stick are 10 small, and this method of securing the spring against rotation has been found to be very practical. The spring, at the end adjoining the cross head, may be anchored in any suitable manner to prevent its displacement endwise of the stick, but for convenience the staple 11 which secures the cross head to the end of the mop stick may be passed over one or more turns of the spring so as to anchor it against displacement endwise along the stick as well as to 15 secure the cross head to the stick.

A lever 14 has a tongue like extension 15 at one end which is bent around a turn of the coil spring at its free end, so as to form 20 a hinge connection between the lever 14 and the spring. The ends of the wire or clamping element 6 are pivotally secured to the lever 14 at a distance from its hinge in the usual manner, and when the lever 14 is operated 25 the spring will serve as a yielding fulcrum and enable the obtaining of a clamping action between the wire 6 and the groove or tunnel in the end of the head. During the assembly of the mop, with the 30 attached lever 14, the spring will be slid over the end of the mop stick before the cross head is applied to the stick, and in doing so the flat portion 10 of the stick will provide a clearance for the hinge extension 15 of the lever. The flat portion 35 10 of the stick which will lie immediately beneath the hinge extension 15, will enable the lever 14 to move lengthwise of the stick 7 without restriction, and will not require a coil spring 12 of unduly large diameter. 40

It will be observed that with this construction, the non-circular socket and mop stick will prevent relative rotation between the cross head and stick, and therefore the 45 head can never become loose upon the stick. The staple or other securing means serves to prevent separation of the cross head from the stick and also may anchor the spring against endwise displacement on the mop 50 stick. The turns of smaller diameter of the spring and the flattened portion 15 of one of the turns of smaller diameter will effectively prevent rotation of the spring about the axis of the mop stick such as would disengage it from engagement with the staple or other securing means. The flat portion 55 10 of the stick, which prevents relative rotation between the stick and cross head, also serves to provide a clearance for the hinged extension 15 of the clamping lever 14.

It will be understood that various changes in the details and arrangements of parts herein described and illustrated for the purpose of explaining the nature of the invention, may be made by those skilled in the art within the principle and scope of the invention as expressed in the appended claims.

I claim:

1. A mop comprising a cross head having 75 therein a socket of non-circular cross section, a stick having one end corresponding in periphery and size to the socket and fitting tightly therein, whereby the cross head will be mounted upon and held against rotation relatively to the head, a coil spring surrounding the stick adjacent the head, and having a turn conforming closely to the non-circular periphery of the stick whereby rotation of the spring on the stick will be 80 resisted by the resiliency of the said spring turn, means for securing the head against separation from the stick and for anchoring the end of the spring adjacent the head against movement lengthwise of the stick, 85 a lever hinged to the other end of the spring, and a clamping bail arranged in clamping relation to the head and connected to the lever for operation thereby into and out of clamping engagement with the head. 90

2. A mop comprising a cross head having 95 therein a socket of non-circular cross section, a stick having one end corresponding in periphery and size to the socket and fitting tightly therein, whereby the cross head 100 will be mounted upon and held against rotation relatively to the head, a coil spring surrounding the stick adjacent the head, the spring at the end adjacent the head closely conforming to the non-circular periphery of 105 the stick and for the remainder of its length loose on the stick, whereby the tight portion will be resiliently held against rotation by the non-circular periphery of the stick, 110 means for securing the head against separation from the stick and for anchoring the end of the spring adjacent the head against movement lengthwise of the stick, a lever hinged to the other end of the spring, and 115 a clamping bail arranged in clamping relation to the head and connected to the lever for operation thereby into and out of clamping engagement with the head.

3. In a mop, a cylindrical mop stick having a segment cut off for a short distance from one end, a head having a socket conforming in size and shape to and receiving the cut off end of the stick, a cylindrical coil spring surrounding the stick and anchored thereto at the end adjacent the head, a lever of sheet metal having a tongue extension bent around a turn of the spring at its free end which also overlies the flat surface formed by the cut off segment, to form a hinge connection between them, a bail ar- 120 125 130

ranged in clamping relation to the head and connected to the lever for operation thereby into and out of clamping engagement with the head, the cut off segment of the stick ⁵ permitting movement of the lever with the spring in a direction endwise of the stick, and facilitating assembly of the mop by

providing clearance for the hinge extension of the lever when the lever and spring are slid over the cut off end during assembly. ¹⁰

In witness whereof, I hereunto subscribe my signature.

BELDEN L. CONCHAR.
